CLAIM

The ornamental design for a microphone, as shown and described.

DESCRIPTION

FIG. 1 is a top-perspective view according to our design;

FIG. 2 is a bottom-perspective view thereof;

FIG. 3 is a top plan view thereof;

FIG. 4 is a bottom plan view thereof;

FIG. 5 is a front view thereof;

FIG. 6 is a rear view thereof;

FIG. 7 is a right-side view thereof; and,

FIG. 8 is a left-side view thereof.

The broken lines depict portions of the microphone that form no part of the claimed design.

1 Claim, 5 Drawing Sheets
